UNITED STATES PATENT OFFICE

63 HENRY W. BATES, OF JACKSON TOWNSHIP, PORTER COUNTY, INDIANA, ASSIGNOR OF
ONE-HALF TO GEORGE HAGA, OF MARSHALL, INDIANA

ANTITHEFT DEVICE FOR FLUID CONTAINERS

63 Application filed May 3, 1930. Serial No. 449,502.

63 My invention relates to improvements in anti-theft device for fluid containers and it relates more especially to the features pointed out in the annexed claims.

65 5 The purpose of my invention is to provide a device which will prevent the theft of liquids from containers of various types and sizes; that makes it impossible to remove liquids from such containers by siphoning or by 10 direct draining; that provides means for locking the inlet and outlet of fluid containers simultaneously; that does not restrict the size of the ordinary filling opening; and that 15 may be applied to automobile tanks whether these are of the gravity or vacuum feed type.

With these and other ends in view I illustrate in the accompanying drawing such instances of adaptation as will disclose the broad underlying features of the invention 20 without limiting myself to the specific details shown thereon and described herein.

Figure 1 is an elevation in section.

Fig. 2 is a top plan view in section on line 2-2 of Fig. 1.

25 Fig. 3 is a top plan view of the lower end, partly in section.

Fig. 4 is a diagrammatic view of the locking plate in position corresponding to the position of the lower end of the tube in 30 Fig. 3.

Fig. 5 is a detached elevation partly in section showing the locking plate and its supporting disk.

Fig. 6 is a diagrammatic view of the locking 35 plate in locked position.

Fig. 7 is a similar view to Fig. 6, showing the parts in unlocked position.

In installing my invention I may use whatever alternatives or equivalents of construction that the exigencies of varying conditions 40 may demand without departing from the broad spirit of the invention.

The safety device may be attached to any desired type of container. It is immaterial 45 whether it be a barrel, a rectangular or round tank, a vacuum or gravity feed supply for automobile, airplane, truck or motor boat uses. The device is readily adapted to any of these requirements by simply changing 50 the length of the safety tube.

As instanced in the drawing the device may be attached to an automobile or other tank with a flat top 1 and a flat bottom 2. The upper end 3 of the safety tube is enlarged in diameter and the lower end 4 of this tube is 55 reduced in diameter so that the volumetric displacement is relatively small, holding a very small supply of fuel. The thief who plans to run away with the car cannot drive very far because the available supply in the 60 tube 4, when it is shut off from the main tank, is so small that it is soon exhausted.

If the car or truck is equipped for gravity feed, the fuel is fed directly through the shut-off 27; and if equipped for vacuum feed 65 the fuel finds exit through the side outlet 28 and the vacuum line 29, to the usual vacuum tank (not shown). In this event all the fuel available will be the quantity in the tube 4 in addition to that in the usual vacuum 70 tank. It is of course obvious that my safety device can also be installed in the regulation vacuum tank. When this is done the only available gas will be that found in the tube 4. 75

The lower end of the safety tube is threaded, externally, at 5 and it is beveled at 25. This bevel cooperates with the beveled entrance 24 leading into the fitting 20. A chamber 26 serves to collect sediment from the 80 fuel under vacuum feeding conditions. When a gravity feed installation is to be made, the vacuum line 29 is removed and the threaded hole in which it was pivoted plugged. The fuel exit will be through the 85 gravity feed outlet through the shut-off 27. In the use of the word "threaded" in the claims I do not limit myself to this form of retention for the tube 4 in the fitting 20 as any desired equivalent may be substituted. 90

There is a side entrance at 23 leading to the chamber 26 when the tube 4 is turned on its axis, so that the opening 6 is in line with the opening 23. This relation only exists 95 when the withdrawal of fuel from the container is authorized. When the withdrawal is unauthorized the tube opening 6 will be removed from the inlet 23. This is effected by turning the tube on its axis a quarter or a half turn by means of the cap 7, secured 100

to its upper end by welding or otherwise, and the wings 8 forming a part of the cap. The upper end 3 of the safety tube fits in the reinforcing ring 19. This ring and the fitting 5 20 may be welded or otherwise attached to the container walls 1 and 2 respectively. If desired, an open cage (not shown) may be made a continuation of the bevel 24 so as to assist in leading the tube 4 into the threaded 10 opening of the fitting 20.

The locking position of the safety tube 3-4 is determined by the bolt-end 15 of the locking plate 14 when it enters the recesses 21 formed in the reinforcing ring 19. This 15 plate has a central opening 17 in which the flattened end 12 of the lock cylinder is positioned. It has a guiding projection 16. The ends 15 and 16 slide in recesses formed on the underside of the cap 7. A recess 13 is 20 formed on the underside of the cap 7 in which the lock retaining washers 10 and 11 are positioned. The lock barrel or escutcheon 9 is served by a conventional type of key 22. The locking plate 14 is retained in place by a flat 25 plate 18. There are two or more of the recesses 21. In the drawing three are shown. One requires a half turn of the cap 7 and another only a quarter turn. The plate 14 is moved positively in both directions through 30 a movement of the key.

The operation of my device is very simple. So long as the container is to permit the removal of its contents without hindrance the tube remains locked, as shown in Fig. 1. 35 Just as soon as it is desired to prevent the removal of the contents the plate 14 is withdrawn from the recess 21 by the key, and the cap 7 with its tube 3-4 is turned around one-quarter of a revolution, until another 40 recess 21 is reached. Here the plate 14 is again made to enter a recess, thus effectually locking the tube and sealing off the exit from the container or tank. In automobile use the key is moved to withdraw the plate 14 from 45 its recess 21, and the entire tube 3-4 is unscrewed from the threaded seat at its bottom and bodily removed from the tank, thus leaving a filling opening of usual size. When filled the tube is replaced and the bolt re- 50 entered into its recess. My device is of course adapted to protect the liquid or gaseous contents of tanks, containers etc.

What I claim is:

1. In anti-theft devices, a container having an inlet thereto and an outlet therefrom, a tube positioned in the inlet and outlet simultaneously, means for threading the tube in the outlet, and means for locking the tube in the inlet.
2. In anti-theft devices, a container having an inlet thereto and an outlet therefrom, a tube threaded into the outlet said tube having an opening registering with an opening leading from the interior of the container to 65 the interior of the tube and an outlet there-

from, means for separating the openings from each other by a partial rotation of the tube on its axis, and means for locking the tube in either one of the two positions.

3. In anti-theft devices, a tube comprising large and small diameter portions, a threaded end for the small diameter said end having a side opening therethrough, a cap at the large end, a key lock operable from the outside of the cap, and a bolt on the inside of the cap and tube operated by the key. 70

4. In anti-theft devices, a container, an inlet thereto comprising a reinforcing ring surrounding the inlet, an outlet therefrom comprising a reinforcing fitting having a threaded recess communicating by a passageway to the inside of the container and having an outlet therefrom terminating outside of the container, a tube threaded at one end adapted to enter the threaded recess and having a side opening near its free end, a cap for the tube engaging the reinforcing ring, and a lock on the cap adapted to hold the tube in a plurality of fixed positions against turning in the ring. 75

In testimony whereof I affix my signature.
HENRY W. BATES.
